UNITED STATES PATENT OFFICE.

CHARLES W. DENNY, WILLIAM E. McLAUGHLIN, AND GEORGE HELWIG, OF MIDDLE-TOWN, OHIO, ASSIGNEES TO THE BARKELEW ELECTRIC MANUFACTURING COMPANY, OF MIDDLETOWN, OHIO, A CORPORATION OF OHIO.

RADIOPHONE PLUG.

Application filed August 13, 1923. Serial No. 657,210.

To all whom it may concern:

Be it known that we, CHARLES W. DENNY, WILLIAM E. McLAUGHLIN, and GEORGE HELWIG, citizens of the United States, residing at Middletown, in the county of Butler and State of Ohio, have invented certain new and useful Improvements in Radiophone Plugs, of which the following is a specification, reference being had therein to the accompanying drawing.

Our invention relates to phone plugs, and in particular to phone plugs for use in radio apparatus.

The object of our invention is to provide a unitary structure for the reception of one or more phones, which phones may be arranged in series.

It is a further object of our invention to provide means of maintaining said phones in firm engagement with the terminals so that there will be perfect connections.

It is an additional object to provide means of radially attaching and detaching the phone wires to the post.

It is a further object of our invention to provide a structure which may be readily assembled and disassembled for repair and adjustment and easily manufactured.

It is also an object of our invention to provide a unitary structure with a standard panel with standard jacks.

Referring to the drawings:

Fig. 1 is a perspective of the plug installed on a panel in contact with a jack;

Fig. 2 is a section through the plug on its main axis;

Fig. 3 is a section on the line *a—a* of Fig. 2;

Fig. 4 is a face view of the insulating plate forming part of collar surrounding contact shaft, with the contact shaft and retaining screw in section taken substantially on the line *b—b* of Fig. 2;

Fig. 5 is a fragmentary section on the line *c—c* of Fig. 2 showing the assembly of the metallic plate, insulating bushing, contact member and retaining screws;

Fig. 6 is a wiring diagram;

Fig. 7 is a section through a four phone post;

Fig. 8 is a side elevation of the special form of spring employed with the cap plate;

Fig. 9 is a plan view of the rear end of the insulating holding ring.

Referring to the drawings in detail:

1 is a panel, while 2 and 3 indicate contacts of a jack. 4 is a collar mounted on the panel for receiving the shaft of the plug.

The plug consists of an annular collar 5 of some insulating material such as is known in the trade as bakelite, and the like. This collar has an interior of two dimensions forming two chambers therein. The forward chamber receives the cap plate 6. This cap plate has five radial cutaway portions 7 for receiving helical springs 8 arranged radially in such cutaway portions in the cap plate. Such radial cutaway portions have the apertures 9 associated therewith on the sides thereof overlapping the spring location for the reception of phone tips 10 which, when inserted therein, engage with the springs and are yieldingly held in position. Five such radial cutaway portions are provided in the cap plate although the exact number is immaterial as such a number depends upon the size and complexity of the phone plug.

It is a further object of our invention to provide a structure which may be readily assembled and disassembled for repair and adjustment and easily manufactured.

It is also an object of our invention to provide a unitary structure with a standard panel with standard jacks.

Referring to the drawings:

Fig. 1 is a perspective of the plug installed on a panel in contact with a jack;

Fig. 2 is a section through the plug on its main axis;

Fig. 3 is a section on the line *a—a* of Fig. 2;

Fig. 4 is a face view of the insulating plate forming part of collar surrounding contact shaft, with the contact shaft and retaining screw in section taken substantially on the line *b—b* of Fig. 2;

Fig. 5 is a fragmentary section on the line *c—c* of Fig. 2 showing the assembly of the metallic plate, insulating bushing, contact member and retaining screws;

Fig. 6 is a wiring diagram;

Fig. 7 is a section through a four phone post;

Fig. 8 is a side elevation of the special form of spring employed with the cap plate;

Fig. 9 is a plan view of the rear end of the insulating holding ring.

Another of these retaining screws connecting the other side of the circuit is designated 16 which fits in the aperture 17 in the cap plate 6. This retaining screw 16 is in engagement with the spring 8 so that a phone tip inserted in an aperture adjacent said spring will be in circuit with the spring and the screw 16, and the parts to which the screw is attached.

The holding ring 5 has an annular chamber 18 divided by the wall 20 which has a pair of slots 21 cut therein oppositely disposed from one another and spaced from one another. The screws 15 and 16 project

through these slots, but the wall 20 separates the cap plate 6 from a metallic plate 22 with which the screw 15 is in contact and in engagement. This plate 22 is also in contact with the shaft 23 and the contact head 24 which engages the spring finger 3 of the jack on one side of the circuit. The other side of the circuit is formed by the sleeve 28 which is in contact with the spring finger 2, the metallic collar 26, and the screw 16 which is in engagement with 26. In order to insulate the two portions of the circuit from one another there is provided the insulating ring 27 between the end of 25 and the head 24, the insulating sleeve 28 which is interposed between 25 and 26 on the one hand and the shaft 23 on the other hand, the insulating plate 29 which is interposed between 26 and 22, and the insulating collar 30 which is interposed between the screw 16 and the plate 22. The flange 31 of the holding ring incases the metallic ring 22, the insulating plate 29, and the end of 26. The inner end 32 of the shaft 23 is seated in a seat 33 of the dividing wall 20.

Thus we have a circuit consisting of the finger 3, the head 24, the shaft 23, the plate 22, the screw 15, the portions of the spring 12, 11 and 8, and the phone tip in the aperture adjacent to the spring as at 34. The phone tip 10 is connected to the phone 35. The phone 35 is connected as at 36 and other phones 37, 38, and 39^a are connected in series. Phone 39^a is connected to the opposite side 35 of the circuit as at 39.

The circuit at 39 extends through the helical spring adjoining the screw 16 which connects the member 26 and the sleeve 25 to the spring finger 2. It is apparent that the combination of any number of phones in series is permissible with this arrangement. It is possible to use either a single set of phones by placing the phone tips in 39 and 34 which have raised edges 40 for identification or to use additional phones by plugging in the circuits as desired. For more than one head set we start with putting a phone tip in one bossed hole or aperture such as 34 and then use the remaining apertures consecutively always carrying the last phone tip back to 39. It is apparent that this phone plug may be arranged for any number of phones depending upon the size of the plug.

55 The removable feature of the cap plate permits of the ready inspection and the adjustment of the several parts and the replacement of the springs if necessary.

Where it is desired to provide a post for attachment to a panel the form is modified as in Fig. 7 where the shaft and head have been eliminated and the two screws 41 and 42 take the place of the screws 15 and 16.

Otherwise the arrangement is exactly the same. This type of plug or post permits of

the use of a plurality of phones in series within a limited area. It also provides means of gripping the phone tips positively and yieldingly in such a way that wear and variation in size is accommodated.

70

It will be understood that various modifications may be necessary in this specific configuration of our invention to suit varying conditions, but we comprehend within our invention such necessary modifications.

75

Having thus fully described our invention, what we claim as new and desire to secure by Letters Patent, is:

1. In a phone plug, a holding ring, a cap plate therein, a plurality of yielding members carried by said cap plate, having a plurality of apertures adjacent said yielding members adapted to receive phone tips, a pair of contact members insulated from one another associated with said ring and plate, and retaining screws respectively in contact with said contact members and respectively in contact each with one of said yielding phone tip retaining means, whereby phones may be attached to said phone plug in series to varying numbers of phones.

80

2. In a phone plug; a holding ring, a cap plate in one face thereof having a plurality of phone tip apertures, a plurality of yielding members arranged in said cap plate adjacent said apertures, retaining members for securing said cap plate on said holding ring, and adapted to contact each with one of said yielding members, contact members associated with said holding ring, said contact members being insulated from one another and being connected to the respective retaining members.

85

3. In a phone plug, a holding ring of insulating material consisting of a forward chamber and a rearwardly disposed chamber, and a partition wall therebetween having an aperture, an insulating cap member having a plurality of apertures therein, said cap member being located in the forward chamber of the holding ring, there being a plurality of cutaway portions adjacent said apertures, a yielding member in each of said cutaway portions, retaining screws, a cap member having apertures for the reception of said retaining screws which pass through the wall to the rear chamber, one of said screws being in contact with a spring in one of the cutaway portions of the cap member into which it projects and the other of the screws being remotely located from said cutaway portions, and an arm connecting one of said yielding members with the second retaining screw, contact members associated together but insulated from each other in the rear chamber of said holding ring, one of said retaining screws being in engagement with one of said contact members and the other of said screws in engagement with the other of said contact members.

4. In a phone plug, a holding ring of insulating material consisting of a forward chamber and a rearwardly disposed chamber, and a partition wall therebetween having an aperture, an insulating cap member having a plurality of apertures therein, said cap member being located in the forward chamber of the holding ring, there being a plurality of cutaway portions adjacent said apertures, a yielding member in each of said cutaway portions, means for insulating said yielding members, retaining screws, a cap member having apertures for the reception of retaining screws which pass through the wall to the rear chamber, one of said screws being in contact with a spring in one of the cutaway portions of the cap member into which it projects and the other of the screws being remotely located from said cutaway portions, and an arm connecting one of said yielding members with the second retaining screw, contact members associated together but insulated from each other in the rear chamber of said holding ring, one of said retaining screws being in engagement with one of said contact members and the other of said screws in engagement with the other of said contact members, a shaft engaging one of said contact members, a projecting sleeve engaging with the other of the contact members, said shaft and sleeve being insulated from one another.
5. In combination in a phone plug of a holding ring, a cap plate having phone tip apertures and retaining spring chambers, contact members insulated from one another, retaining screws joining said ring, cap plate, and contact members to one another, said screws being in contact with the respective contact members, yielding means for engaging phone tips, each of said retaining screws being associated with one of said yielding means, whereby phones may be connected to said cap plate in series in varying numbers of phones.
6. In combination in a phone plug of a holding ring, a cap plate having phone tip apertures and retaining spring chambers, contact members insulated from one another, retaining screws joining said ring, cap plate, and contact members to one another, said screws being in contact with the respective contact members, yielding means for engaging phone tips, each of said retaining screws being associated with one of said yielding means, one of said yielding means being in contact with a retaining screw by means of an arm while the body of the spring is remotely located from the retaining screw.
7. In combination, a holding ring having a central partition dividing chambers therein, communicating passageways through said dividing wall, a cap plate in one of said chambers, a contact plate in another of said chambers, retaining screws passing through the apertures in the walls and holding said cap plate and contact members together as a unit, each of said screws being in engagement with the respective contact members, said contact members and screws being insulated from one another respectively, helical springs radially disposed in said cap plate associated with apertures in said plate to receive phone tips, said helical springs being insulated from one another, one of said helical springs being also associated with one of the retaining screws, another of said helical springs being associated with the other of said retaining screws, but remotely located therefrom being connected thereto by an arm, whereby phones may be connected to said cap plate in series in varying numbers of phones.
8. A contact pin having a contact head, a contact sleeve surrounding said pin, and spaced from said head, but insulated from both the pin and the head, a support of insulating material mounted adjacent one end of said pin and sleeve, a second support of insulating material carrying a plurality of yielding means and having a plurality of apertures adjacent said yielding means for the reception and retention of phone tips, and a pair of spaced retaining screws holding said insulating members to one another and serving to complete the circuit on either side with the respective contact pin and sleeve and said yielding means.
9. A contact pin having a contact head, a contact sleeve surrounding said pin, and spaced from said head, but insulated from both the pin and the head, a support of insulating material mounted adjacent one end of said pin and sleeve, a second support of insulating material carrying a plurality of yielding means and having a plurality of apertures adjacent said yielding means for the reception and retention of phone tips, and a pair of spaced retaining screws holding said insulating members to one another and serving to complete the circuit on either side with the respective contact pin and sleeve and said yielding means.
10. A contact pin having a contact head, a contact sleeve surrounding said pin, and spaced from said head, but insulated from both the pin and the head, a support of insulating material mounted adjacent one end of said pin and sleeve, a second support of insulating material carrying a plurality of yielding means and having a plurality of apertures adjacent said yielding means for the reception and retention of phone tips, and a pair of spaced retaining screws holding said insulating members to one another and serving to complete the circuit on either side with the respective contact pin and sleeve and said yielding means, said parts being arranged for connecting phones which are attached to the phone tips in series.
11. A contact pin having a contact head, a contact sleeve surrounding said pin, and spaced from said head, but insulated from both the pin and the head, a support of insulating material mounted adjacent one end of said pin and sleeve, a second support of insulating material carrying a plurality of yielding means and having a plurality of apertures adjacent said yielding means for the reception and retention of phone tips, and a pair of spaced retaining screws holding said insulating members to one another and serving to complete the circuit on either side with the respective contact pin and sleeve and said yielding means.

and perfectly corresponding when compared side with side, the pre-predilection of the yield stress and yielding stress being retained for increasing and decreasing stress rates, being increased or reduced when the rates are increased or decreased. The yielding stress value is however observed to be constant and subject to even the transposition of

load if they are completely retained and transposed.
